TAG

Filed Aug. 25, 1931

UNITED STATES PATENT OFFICE

RENÉ HARTGENBUSCH, OF COLOGNE-NIPPS, GERMANY, ASSIGNOR TO A. KIMBALL COMPANY, OF NEW YORK, N. Y., A CORPORATION OF NEW YORK

TAG

Application filed August 25, 1931. Serial No. 559,217.

This invention relates to tags or tickets and a method of making the same, the invention being more particularly related to devices of this kind for attachment to dry goods, bolted or rolled goods, articles of wearing apparel and flexible articles generally, and which are adapted to bear or receive markings indicative of price, style or size.

An object of the invention is to provide a tag or ticket of the character described which is capable of attachment to the goods without the use of pins, clips or other metallic fasteners, and one which will be easy to attach to the goods as well as to be removed therefrom.

A further object of the invention is to provide a marking device the construction of which includes a tongue for interlocking engagement with the goods, and a backing piece or abutment for limiting the movement of the tongue in the direction of the pull exerted toward the body of the goods, due to the attachment of the device to the goods. Another object of the invention is the provision of a construction which, in a desired embodiment, will permit the use of toothed edges for better retaining the goods on the tongue.

The invention also relates to a method whereby, in a simple and economical manner, a series of marking tags or tickets may be produced at one time from blank stock, the method involving the step of cutting the stock to provide certain openings and tongues for the several tags and folding the stock so that a backing part will be provided for the tongues of the several tags. After being cut and folded, the stock is divided into the individual tags.

With the foregoing and other objects in view, the invention consists in the combination of members and arrangement of parts so combined as to coact and cooperate with each other in the performance of the function and the accomplishment of the results herein contemplated, and further consists in the new and original method steps hereinafter described.

Several simple and practical embodiments of the invention, as reduced to practice, are

illustrated in the accompanying drawing, in which:

Figure 1 represents a fragmentary plan view of a blank sheet provided with the tongues and slots necessary for producing a plurality of tags in accordance with my invention;

Fig. 2 is a similar view, showing the sheet folded so that the marginal edges of the slotted portions will form the abutments behind the tongues;

Fig. 3 is a plan view of an individual tag separated from the sheet and attached to a piece of fabric;

Fig. 4 is a longitudinal sectional view, 65 taken on the line 4—4 of Fig. 3;

Fig. 5 is a view similar to Fig. 1, but showing another form of construction;

Fig. 6 is a fragmentary plan, showing the sheet illustrated in Fig. 5 in folded condition, 70 to provide abutments behind the tongues;

Fig. 7 is a plan view of an individual tag separated from the stock construction shown in Fig. 6;

Fig. 8 is a longitudinal sectional view, 75 taken on the line 8—8 of Fig. 7; and

Fig. 9 is a detail view showing toothed or serrated edges for gripping the fabric.

Referring now in detail to the accompanying drawing, and first to the form of construction illustrated in Figs. 1 to 4, inclusive, the numeral 10 designates in general a fragmentary portion of a blank sheet which may consist of cardboard, celluloid or other stock material suitable or approved for use in the production of tags or tickets. At the places where the individual tags as 11 are to be cut off or separated, the sheet may be provided with elongated transversely extending openings 12 and suitable separating lines 13, although these indicator parts for the separation of the individual tags are not essential.

The sheet may be provided, longitudinally thereof, with a folding line 14 parallel with the longitudinal edge 15. Below the folding line 14 and for each of the individual tags, there is provided a rectangular opening 16, the longitudinal edges 17 and 17' of which are parallel to the folding line 14. On the opposite side or above the folding line 14, 100

there is provided for each individual tag a tongue 18, cut through the body of the sheet so as to provide parallel slots or spaces 19 at opposite sides of the tongue and a slot or space 20 along the free end of the tongue. Each tongue is cut out so that adjacent the folding line 14 it will have a portion integral with the sheet, while its free end portion will be pointed towards the longitudinal edge 15 of the sheet. The tongue is thus integrally united along one side with the sheet while the three remaining sides are separated from the sheet by open spaces; and it will be observed in this connection that the tongue, cut from the body of the sheet in this manner, lies in the plane of the sheet.

The sheet, having thus been provided with openings and tongues, is next folded, the longitudinally extending part A above the folding line 14 being folded forwardly and pressed down flat upon the part B so that, as shown in Fig. 2, the openings 16 will be located behind the tongues 18. The openings 16 are of such size that the marginal portions 21 of the part B, which portions extend along the edges 17 of the openings 16, serve as abutments for the free ends of the tongues, so that while the tongues are free to move forwardly from and to the plane of the sheet, they cannot move backwardly because of the presence of the abutments. The spaces or slots 19 at the opposite sides of the tongues come in direct open communication with the openings 16. The folded-over part A may be secured firmly to the part B by means of any suitable adhesive or cementitious substance. When the parts A and B have thus been secured together, it will be recognized that each of them reinforces the other, and that while each of the tongues may be moved forwardly from the plane of the sheet, it cannot be moved rearwardly therefrom because of the presence of the abutting portion 21.

In Figs. 3 and 4, I show an individual tag 11 separated from the sheet and attached to a portion of fabric 22 to be retained thereby. In order to attach the tag to the fabric, it is only necessary to press the tongue 18 forwardly from the abutment 21 and then insert the edge 22' of the fabric through the space 20 at the free end of the tongue and through the spaces 19, 19 at the opposite sides of the tongue, finally bringing the edge 22' up over the front face of the tongue so that the fabric will be disposed across the front face of the tongue and extend rearwardly through said openings 19, 19 and 20. In this way the fabric will be interlocked over the tongue and gripped between the edges of the tongue and the adjacent edges of the sheet. When the fabric has thus been interlocked and gripped in place any pull directed rearwardly or towards the body of the fabric of which the portion 22 is a part, will only have the effect of drawing the tongue tightly against the

abutment 21; and owing to the constant pull or tension of the fabric rearwardly upon the tongue, the tag will not accidentally become detached. Manifestly, when it is desired to detach the tag, it is only necessary to move the tongue forwardly from the abutment and thereupon draw the fabric downwardly over the face of the tongue until the fabric can be withdrawn from the tag.

In Figs. 5, 6 and 7, I illustrate a modified form of construction in which the folding is effected in such manner that there is no occasion to provide openings 16. In this modified form, 23 designates the longitudinal line of fold and the lower portion C of the sheet is folded rearwardly and upwardly to lie flat against the back face of the part D; the line of fold 23 being provided in such relationship that the marginal portion extending along the free edge 24 of the part C will constitute abutments 25 for the tongues 26 located in the part D and cut therefrom so as to provide side spaces or slots 27 and an end space or slot 28. The part C is firmly secured to the part D by adhesive or cementitious substance. The sheet, when thus folded, is divided into individual tags 29. With this form, there is no change in the manner in which the tag is attached to the fabric, it being only necessary in order to effect the attachment, to press the tongue 26 away from the abutment and insert the fabric through the slots and interlock it over the face of the tongue.

In order to provide a positive gripping action, the free edges of the tongue may be toothed or serrated, as shown at 30 in Fig. 9; and in addition to this, if it is desired, the edges of the walls defining the spaces at opposite sides of the tongue may also be toothed or serrated as at 31.

Each blank may be of a dimension sufficient to provide for the production at one time of a series of tags; and it will be readily understood by those familiar with the art that the openings and tongues may be die-cut so that upon the folding of the sheet the parts will come in proper registration with the abutments located behind the free end portions of the tongues.

Tags produced in accordance with the present invention are simple and economical to manufacture. They are easy to attach; and when once attached they remain attached until manually removed. The tags of my invention eliminate the use of metal fasteners or pins which mutilate the fabric.

While I have illustrated and described my invention as comprising a particular mode of treatment and as taking certain selected forms, it will be understood that changes and alterations may be made in the particular details set forth and in the particular forms of construction without departing from the spirit of the invention, and hence I do not

limit myself to the particular details set forth or to the particular forms of construction, but consider myself at liberty to make such changes and alterations as fairly come within 5 the scope of the appended claims.

I claim:—

1. A tag of the character described comprising a sheet member folded upon itself, forming a front member and a back member 10 abutting against one face of said front member, a tongue in the front member cut therefrom to have one side integral with said front member while the remaining sides are separated by intervening spaces, the back member 15 having a space cut out underneath the tongue to permit passage therethrough of a fabric, said tongue extending beyond the space in the back member for receiving and retaining the fabric passed through said 20 space to cooperate with the back member in gripping the fabric, and preventing backward movement of the tongue under the pull of the fabric exerted from that direction.

2. A tag of the character described comprising a strip of sheet material folded upon itself to provide a front member and a back member, a tongue provided in the front member, integrally connected therewith to normally lie in the plane thereof, said tongue 25 being connected to the front member along one side and otherwise separated therefrom by a space, said back member having a portion forming an abutment behind the tongue to prevent backward movement of the tongue, 30 and also having an open portion adjacent the abutment to permit, on movement of the tongue forwardly from the abutment, the passage of fabric through the open space for 35 interlocking engagement with the tongue.

3. A tag of the character described comprising a strip of sheet material folded upon itself to provide a front member and a back member, a tongue provided in the front member, integrally connected therewith to normally lie in the plane thereof, said tongue 40 being connected to the front member along one side and otherwise separated therefrom by a space, said back member having a portion forming an abutment behind the tongue 45 to prevent backward movement of the tongue, and also having an open portion adjacent the abutment to permit, on movement of the tongue forwardly from the abutment, the passage of fabric through the open space for the 50 application of the fabric across the tongue, the free edges of said tongue and the adjacent edges of the front member defining said space, together constituting means for 55 clamping the fabric, and certain of the free edges of said tongue being serrated for gripping the fabric.

In testimony that I claim the foregoing as my invention, I have signed my name hereto.

RENÉ HARTGENBUSCH.
